UNITED STATES PATENT OFFICE.

IVAN C. BELL, OF DALLAS, TEXAS, ASSIGNOR TO THE GUIBERSON CORPORATION, OF DALLAS, TEXAS, A CORPORATION OF DELAWARE.

TUBING STRIPPER.

Application filed October 4, 1924, Serial No. 741,772. Renewed October 4, 1926.

My invention relates to packers for closing the upper end of a casing about the well tubing in handling pipe, particularly while it is being introduced into or removed from the well in deep well operations.

While withdrawing tubing from wells in which there is a certain amount of gas pressure, difficulty is frequently experienced, due to the fact that the fluid will be forced up with the gas and the tubing and will be thrown upon the derrick platform, and upon the operators handling the pipe. Even in wells in which very little gas pressure is present there is oil upon the pipe and there may be a thick layer of oil and mud tending to obstruct the proper handling of the joints of tubing.

It is an object of my invention to provide a packer to be used in connection with the ordinary type of casing head and adapted to fit about the pipe which is being handled in such manner as to prevent the escape of oil or other liquid and gas from the well. It is also intended to wipe the pipe clean of oil or mud so that the pipe may be more readily handled as it is removed.

Another object is to provide a packer of the type described which will allow the removal of the pipe from the well and prevent the escape of gas in such manner that the gas may be carried off laterally through pipes connected with the casing head and thereby saved.

Another object is to provide a packer to be used with casing heads which may be easily and quickly applied to the pipe as it is operating in the well with a minimum of manipulation. Other objects and advantages, and the means by which the said objects are accomplished, will more clearly appear from the description which follows.

Referring to the drawings herewith, Fig. 1 is a top plan view of the packer embodying my invention, the tubing being shown in section. Fig. 2 is a central longitudinal section through a casing head and packer embodying my invention, the pipe being shown in elevation. Fig. 3 is a side view of the said packer, certain parts of the casing head being broken away for greater clearness. Fig. 4 is a bottom plan view of the packer and Fig. 5 is a transverse section on the plane 5—5 of Fig. 3.

In Fig. 2, my device is shown in combination with a casing head 1 of ordinary con-

struction secured at the upper end of the casing 2, and having a plurality of lateral pipes 3 connected therewith for carrying off gas or other fluid coming from the well.

A tubing 4 of the usual construction having a coupling 5 thereon, is shown within the casing and extending above the casing head. For use while this tubing is being raised from or lowered into the well, and particularly while it is being taken from the well, I have provided a packer for closing the space between the casing head and the tubing to prevent the passage of fluid from the upper end of said casing head.

This packer is adapted for use in combination with a bushing 6 cylindrical in general outline and having a radial flange 7 at its lower end to be engaged below set screws 8 in the upper end of the casing head to hold the bushing in the seat 9 ordinarily present in the usual construction of casing heads.

A somewhat larger radial flange 10 is formed at the upper end of the bushing to provide for an inner seat 11 to take the place of the seat 9 of the casing head when the bushing is in position. This seat is left open to receive a bushing for pipe supporting slips or other means usually employed in handling pipe.

As shown particularly in Figs. 1 and 4, the bushing is split longitudinally into two sections and cooperating lugs 12 and 13 on the two halves forming the bushing are adapted to receive a vertical pin 14 forming a pivot for the two halves of the bushing. In this manner the bushing is hinged about the pin 14 and may swing open on that point. The opposite sides of the two cooperating parts are formed with spaced lugs 15 and 16 projecting laterally from the two halves of the bushing. On the lug 15 a latch member 17 is hinged upon a pin 18. The head 19 of the said latch is adapted to fit between the upper and lower halves of the lug 16 when the bushing is in closed position so as to assist in holding the bushing closed. This form of latch is an old one, not forming an essential part of my invention.

Adjacent the lower end of the bushing 6 is an inwardly projecting flange 20 leaving an opening 21 within the bushing through which the tubing may easily pass. Below the flange 20 is formed a seat 22 for the upper end of the flexible packing sleeve or tubing stripper 23.

The said packing sleeve has an upper head 24 fitting within the seat 22. Below the head an annular recess 25 is formed to receive a split ring 26 of metal or other rigid material by means of which the head may be clamped tightly within the seat 22. The said ring 26 is secured to the bushing 6 by means of bolts or screws 27 shown in Fig. 3. A plurality of these bolts are secured through 10 openings in the ring 26, through the head 24 of the packer, and screwed within the flange 20 of the bushing. Below the securing means thus provided, the outer face of the bushing is tapered downwardly to its lower end. 15 The inner face of the packing sleeve is of larger diameter than the tubing except at its upper end at 28 and again adjacent the lower end at 29. At these two points the inner diameter of the packing sleeve is adapted to 20 engage against the outer surface of the tubing and because of its flexible construction, will allow the passage of couplings 5 there-through without allowing the escape of fluid around the tubing. Below the packing 25 surface 29 the inner surface of the sleeve is beveled outwardly at 30 to receive the coupling and the same beveled surface is provided at the upper and lower ends of each of the packing faces 28 and 29.

30 The packing sleeve may be made of rubber or of wear-resisting flexible composition, and I preferably form the meeting edges of the two halves of the packer sleeve with offset jointed faces, as shown at 31 in Fig. 5. 35 It will be noted that these two parts inter-fit in such manner that the two halves are interchangeable. This will allow for the spreading of the two halves of the packer as the couplings are drawn through the same 40 without allowing leakage of fluid laterally.

The two halves of the packer thus formed may, if desired, be held firmly and resiliently together by means of springs 32, one on each of the halves of the packing sleeve. As 45 shown in Figs. 3 and 4, these springs are secured through openings in the ring 26 at the upper ends and are extended downwardly along the tapered surface and have a curved section 33 bearing against the sleeve near the lower end. Said springs are under compression to hold the parts of the sleeves together but will allow a certain lateral play to accommodate the passage of the pipe couplings. I contemplate dowel pins 34 between 50 the meeting faces of the bushing to assist in holding the parts of the bushing in registered position in an obvious manner.

In the operation of my device the packer 55 may be easily fitted about the tubing and secured within the casing head in the manner already described, and when in this position, the tubing may be raised or lowered without allowing the passage of fluid between the tubing and the casing head. While coming 60 out of the well the pipe may be drawn up-

wardly through the packer which will allow the collar 5 of the tubing to pass therethrough without allowing the escape of fluid. The packing faces 28 and 29 are spaced apart so that the packer will be engaging the face 70 of the tubing itself at one point at all times. After the coupling has passed, the packing sleeve will hold resiliently in position, thus preventing the escape of gas.

It will be noted also that the packer is so 75 designed that the gas pressure will assist in maintaining a close fit about the tubing and that this assistance will be most positive, the greater the pressure of the gas or oil. This shaping and positioning of my packer 80 whereby the gas or liquid pressure helps in maintaining a tight closure is an important feature of my invention.

It will be noted that the pipe will be 85 wiped free of oil and mud as it issues from the well, and may be easily handled without inconvenience. Gas or other fluid which might escape from the upper end of the casing about the tubing may, if desired, find 90 an exit through the lateral pipes 23 in any 95 manner desired.

The advantages of this construction will be obvious to those skilled in the art without further description. What I claim as new and desire to protect by Letters Patent is:

1. In combination with a casing head and a pipe therein, a packer comprising a bushing, means to secure said bushing in said casing head, a packing sleeve of compressible material secured to and carried within said bushing and spaced from said casing head, and means to hold said packing sleeve resiliently against said pipe.

2. In combination with a casing head and a pipe therein, a packer fitting in said casing head comprising a bushing longitudinally divided into two parts, means to hold said parts together, a divided packing sleeve, and means to secure said sleeve to said bushing, said sleeve extending downwardly and spaced from said casing head about the tubing, whereby fluid pressure in said casing head will hold the sleeve resiliently against 115 said pipe.

3. In combination with a casing head, a tubing therein, a bushing fitting between said casing head and said tubing, a downwardly tapered packing sleeve of resilient material secured to said bushing and having a fluid-tight fit therewith, said packing sleeve having a bore formed to allow the passage in both directions therethrough of the collars on said tubing, the lower end of said sleeve having a portion in continuous circumferential contact with said tubing and held in such contact by the fluid pressure of the fluid in the casing head around said sleeve.

4. In combination with a casing head, a 130

- tubing therein, and a hinged bushing secured detachably in said casing head, of a longitudinally divided downwardly tapered packing sleeve below said bushing, means to secure said sleeve to said bushing, and means to allow a limited expansion of said packing sleeve in the manner described. 5
5. In combination with a casing and a pipe extending therethrough, of a bushing 10 on said casing, a packing sleeve in said bushing about said pipe, and spaced inwardly-extending ribs on said sleeve presenting cylindrical surfaces held resiliently against said pipe, said ribs being positioned apart 15 to contact with the said pipe to maintain a tight closure at one point at least, when a collar on said pipe is forced through said sleeve.
6. A packer for casing heads comprising 20 a bushing adapted to seat in said casing head and allow the passage of tubing therethrough, a packing sleeve secured in fluid tight relation to said bushing, and plurality of spaced cylindrical faces on the inner periphery of said sleeve shaped to fit said tubing at spaced points thereon and adapted to expand a limited amount in the manner described. 25
7. A packer for attachment to a divided bushing in a casing head comprising, a downwardly extending divided sleeve within said casing head, spaced inner cylindrical faces on said sleeve to contact at each end with the tubing, and means to secure the sleeve to said bushing. 35
8. A packer of the character described comprising a bushing, and a flexible packing sleeve secured within the bushing and provided with a depending flexible gripping portion free from exterior contact and 40 having its lower edge terminating in a continuous annulus for forming a fluid tight joint with a pipe when the depending portion of the sleeve is subjected to external fluid pressure. 45
9. A packer of the character described comprising a split bushing having its members hinged together and provided with suitable fastening means, a split sleeve having its members secured in the divided portions 50 of the bushing, said sleeve having overlapping contacting edges and also being provided with a depending flexible gripping portion free from exterior contact and having its lower edge terminating in a continuous annulus for forming a fluid tight joint with a pipe when the depending portion of the sleeve is subjected to external fluid pressure. 55

In testimony whereof I hereunto affix my ⁶⁰ signature this 26th day of September, A. D. 1924.

IVAN C. BELL.
